UNITED STATES PATENT OFFICE.

ROBERT H. HOUK, OF JOLIET, ILLINOIS.

THERMOSTATIC SWITCH.

Application filed July 20, 1922. Serial No. 576,387.

To all whom it may concern:

Be it known that I, ROBERT H. HOUK, a citizen of the United States, residing at Joliet, in the county of Will and State of Illinois, have invented new and useful Improvements in Thermostatic Switches, of which the following is a specification.

This invention relates to electric switches which are controlled by a thermostat, and its object is to provide a switch of this kind embodying certain novel and improved features of construction and modes of operation as will be pointed out in the detailed description appearing hereinafter.

In order that the invention may be better understood, reference is had to the accompanying drawings, wherein:

Figure 1 is an elevation of the complete apparatus,

Fig. 2 is a vertical section on the line 2—2 of Fig. 1, and

Fig. 3 is a detail view of a modification. Referring specifically to the drawings, 10 denotes a suitable base which supports the apparatus. The thermostatic element is a bent tube 11 having one of its ends rigidly fastened to the base, its other end being left free so that it may move in a direction outwardly of the first-mentioned end in response to a temperature increase, and toward the latter in response to a drop in temperature.

The base 10 also supports a dial plate 12 across which is movable a pointer 13 carried by an arm 14 of insulating material. The arm 14 is pivoted at one end, and its other end carries the pointer 13, said last-mentioned end being slotted, as shown at 15, to straddle the plate 12.

40 Into the base plate 10 and through a metal plate 16 secured to the face of the base plate 10 is passed a screw 16^a which passes loosely through a small cylindrical block 17 having a reduced bottom portion 17^a which seats in an aperture 14^a in the rear or inner end of the arm 14, whereby the pivotal mounting of said arm is obtained. The forward end of the arm 14 carrying the pointer 13 also carries a pair 50 of spring fingers 18 which bear against the under side of the plate 12 with sufficient pressure so that the arm 14 works tight and remains in the position it may be placed.

55 The screw 16^a pivotally supports a switch arm 19 of insulating material extending parallel to the arm 14 and adapted to swing

therewith, but free to swing independently of the latter to a limited degree for a purpose to be presently described. The pivotal axes of the arms 14 and 19 therefore 60 coincide.

The forward end of the arm 14 carries a bracket 20 having upstanding, laterally spaced end portions 20^a through which are threaded screws 21. The arm 19 carries a 65 finger 22 at its forward extremity having outwardly directed branches 22^a which are located between the inner opposite ends of the screws 21.

One side of the electric circuit to be controlled is connected to the bracket 20, and the other side is connected to the finger 22. The bracket 20 and the finger 22 are made of brass or other electro-conductive material. On the base 10 are mounted binding posts 23 to which the main circuit wires 24^a are connected, and from these binding posts, conductors 25 are carried to the bracket 20 and the finger 22, the connections being made by suitable clips 26. The base 10 also carries a guide and clamping member 27 for the conductors 25.

70 The movement of the thermostatic element 11 is adapted to be transmitted to the switch arm 19 by means of a bar 28. One end of this bar is threaded, as shown at 28^a, and passes loosely through an ear 11^a on the free end of the element 11. Lock nuts 29 carried by the threaded end 28^a of the bar 28 rigidly couple the same to the free end of the element 11 upon running said nuts on the threaded end in a direction to tightly engage opposite sides of the ears 11^a. Intermediate its ends, the bar 28 has a recess 28^b into which extends a pin 30 extending 80 downwardly from a plate 30^a secured to the bottom of the arm 19. The plate 16 carries a guide 31 for the bar 28.

85 The apparatus is designed to be adjusted to respond to a variation in any desired degree of temperature. This is done by swinging the arm 14 to bring the pointer 13 to the graduation on the dial 12 denoting the degree of temperature which is to be maintained. Before this can be done, the lock nuts 29 must be backed to uncouple the bar 28 from the free end of the thermostatic element 11, and after the arm has been swung to set the pointer as described, the lock nuts must be operated to again couple 90 the bar to the thermostatic element. To facilitate the setting of the pointer 13, the

arm 14 has a knob 32 back of the former. The switch arm 19 carrying the contact finger 22 swings with the arm 14 and hence said finger follows the switch contact points formed by the screws 21. If now there is a rise in temperature, the free end of the thermostatic element moves outwardly, and through the bar 28 and its connection with the switch arm 19 through the pin 30, said arm is made to swing to bring one of the branches 22^a of the contact finger 22 into contact with the opposite screw 21, thereby closing the electric circuit. When a drop in temperature occurs, the parts move in the opposite direction to that just described, and the other branch of the contact finger swings over to engage the opposite contact screw, so that the circuit is again closed.

The switch can be used in connection with any electro-responsive apparatus, such as a magnet for sounding an alarm, or a motor for operating a valve or any other mechanism. The preferred embodiment of the invention has been disclosed but it will be understood that various changes and modifications may be made without a departure from the spirit and scope of the invention as claimed hereinafter. Fig. 3 shows one of these modifications. Here, the bar which provides the operative connection between the thermostatic element and the movable switch arm 19, is a rack bar 32 which is in

mesh with a pinion 33 carrying the switch arm. Various other modifications will readily suggest themselves to those skilled in the art to which the invention pertains.

I claim:

A thermostatic switch comprising a base, a dial secured to the base, a main pointer arm of insulating material having its upper portion formed with a slot receiving the lower edge portion of said dial, a spring carried by said main pointer arm and engaging the rear side of said dial to hold the main pointer arm in position, a pivot element supporting said main pointer arm, a switch arm of insulating material mounted on said pivot element and having a contact finger, contacts carried by said main pointer arm and located on opposite sides of said contact finger, a longitudinally movable bar having its intermediate portion formed with a slot opening out through the lower end thereof and slidably receiving a pin carried by said switch arm, said slot being extended at right angles to the axis of the bar and having side walls in engagement with said pin whereby the longitudinal movement of the bar will operate said pin and the switch arm carrying the pin, and a thermostat connected to said bar.

In testimony whereof I affix my signature.

ROBERT H. HOUK.
